UNITED STATES PATENT OFFICE.

JAMES M. DODGE, OF PHILADELPHIA, PENNSYLVANIA, ASSIGNOR TO THE DODGE COAL STORAGE COMPANY, OF NAUGATUCK, CONNECTICUT.

REVERSIBLE LOADING AND UNLOADING CONVEYER.

SPECIFICATION forming part of Letters Patent No. 402,811, dated May 7, 1889.

Application filed October 15, 1887. Renewed March 20, 1889. Serial No. 304,053. (No model.)

To all whom it may concern:

Be it known that I, JAMES M. DODGE, of Philadelphia, in the county of Philadelphia and State of Pennsylvania, have invented a new and useful Improvement in Reversible Loading and Unloading Conveyers; and I do hereby declare that the following is a full, clear, and exact description thereof, reference being had to the accompanying drawings, making part of this application.

My present invention relates to an improvement in an apparatus or contrivance adapted to convey coal, culm, and other material from a given source of supply and pile the same into an extensive heap, and to also, by slightly varying the action of the machinery, reconvey such material from a pile or heap to a given point or locality for removal and transportation.

In another application filed by me, Serial No. 250,316, I have shown and described all the features of such a contrivance or apparatus, and the present one is substantially the same, except with reference to the means by which the chain conveyer is rendered capable of operating upon the material to be handled in both directions—that is, so as to convey it from a locality of supply and pile it up, and to also remove it from a pile to a given point; but in order that my present invention may be perfectly understood, I will now proceed to describe the same as applied to substantially such a contrivance as is shown and described in my other application, referring by letters to the accompanying drawings, in which—

Figure 1 is a top or plan view of a chain-conveyer contrivance made according to my present invention, and showing by dotted lines certain adjustments of some of the parts thereof, for a purpose to be presently described. Fig. 2 is a side view or elevation of said apparatus, also showing in dotted lines certain other adjustments of some of the parts, for a purpose to be presently described. Fig. 3 is a detail or partial top view of some of the parts, drawn on an enlarged scale. Fig. 4 is a side view of some of the parts seen in side elevation at Fig. 2, but drawn on an enlarged scale.

In the several figures the same parts will

be found designated by the same letters of reference.

A represents an ordinary railroad trestle-work, on which is constructed a track, a, to constitute such an elevated railway as is usually employed where coal and other material are to be dumped in heaps or piles from transportation-cars.

At any desired point in the length of said elevated railway is constructed a suitable frame-work, b, located near the bottom of the trestle-work, within which are mounted in suitable bearings the horizontal drive-shaft of a sprocket-wheel, c, (that is designed to operate the chain conveyer,) and the vertically arranged shafts of the two sets of horizontal chain-wheels or idlers d d and e e, in contact with the peripheries of which wheels the drive-chain runs under certain circumstances, which will be hereinafter explained.

D is an ordinary cable-chain provided with suitable flights or carriers, f, and passing at the upper end of the run of the chain around a suspended chain-wheel, B, the shaft g of which is mounted in a V-shaped frame, h, the apex of which is flexibly connected with a swivel, i, which is mounted in a cross-head, E, all as clearly shown. Said cross-head E is connected by threaded shafts or rods J with a somewhat similar cross-beam, L, that is suspended by means of a loop, o, and through the medium of a block and tackle from the upper end of the pole or mast C. This mast or pole C rests at its base on the ground, and is maintained in the proper erect position by means of suitable guy-ropes or draft-cables, which extend from its upper end to suitable anchorages at the surface of the earth, and one of which, k, extends from the top of the pole obliquely downward and directly backward, so as to pull in direct opposition to the draft-strain of the chain conveyer, while the other two guys, l l, extend downward obliquely and laterally, as shown.

The suspended cross-beam L is supported by means of one end of a rope or cable, as seen at p, that passes upward and over a suitable pulley or sheave-block, and thence downward, as seen at q, to any suitable anchorage or temporary holdfast, and each of the screw-

rods J is provided, immediately in the rear of the cross-beam L, with a nut, m, the external portion or periphery of which is toothed to form a sprocket-wheel and to engage with an endless chain belt, M, all as clearly shown, one of the said nuts and toothed devices m being formed or provided, as shown, with a hand-wheel, n.

P represents an ordinary elevator designed 10 to elevate or carry off from the locality of the lower end of the run of the chain conveyer any material brought to such locality by said conveyer and to discharge the same into cars on the elevated track a for trans- 15 portation.

At Fig. 2 the dotted line 1 2 3 4 indicates the profile of a pile of material heaped up by the action of the chain conveyer D when the latter is run in the direction indicated by the 20 arrow in full lines at said figure, while the dotted lines at Fig. 1 represent the shifting or adjustment of the pole or mast and the upper end of the endless chain conveyer laterally in both directions, for a purpose to be presently 25 explained; and the dotted position of the chain conveyer and the adjustable devices by which its upper end is supported (seen at Fig. 2) illustrate a vertical and downward adjustment 30 of the conveyer and a reversal of its direction of travel, as indicated by the dotted arrow at Fig. 2, for a purpose to be presently described.

In the operation of a contrivance such as shown in the drawings and thus far described, 35 for the purpose of removing coal or other material from a given locality at which it may be dumped from the elevated track a, the parts being all set and operated in the position shown by full lines in the drawings and the 40 drive-wheel c rotated by any suitable motive power in the proper direction, the material dumped at the vicinity of the lower end of the chain conveyer D is scraped or carried away from the point of discharge by the action of 45 the lower set or run of flights, f, and is gradually heaped or piled up into a mass of extensive proportions, as indicated by the profile dotted line 1 2 3 4 at Fig. 2, and for the purpose of increasing the magnitude of the pile 50 or heap without changing the position of the lower end of the chain conveyer the mast or pole C may be gradually and periodically shifted in the directions and to the positions indicated by the dotted lines at Fig. 1, the 55 chain of the conveyer under such circumstances of adjustment being brought into lateral contact with the peripheries of one or the other set of horizontal chain-wheels or idlers d d and e e.

60 Whenever it may be desired to use the contrivance shown for the purposes of reconveying the pile or mass of material accumulated back to the locality from which it was originally taken, it is only necessary to reverse 65 the position of the conveyer-chain D, so that its flights f will stand in the positions indicated by the dotted lines at Fig. 2, and to then

reverse the direction of travel or run of the conveyer-chain, as indicated by the dotted arrow at said figure, when the lower run of the flights f will then operate to carry or convey the material at the top surface of the pile backward to the locality of the lowermost chain-wheel, c, from whence the discharged and accumulating material may be elevated 75 by an ordinary elevator, P, (or other suitable means,) and discharged into the dumps or cars on the elevated track a for transportation. During the use thus of the endless chain conveyer for the purpose of carrying off the material composing the pile the upper end of said chain conveyer has to be gradually lowered until at the finishing of the operation of the removal of the material it may have been brought down into about the horizontal position indicated by the dotted lines at Fig. 2. To effect this lowering of the upper run of the endless chain conveyer and to at the same time keep the conveyer-chain sufficiently taut, the cross-head L, with its attachments, 80 is permitted to descend gradually or periodically by gravity by letting up on the block-and-tackle fixture, or letting out the rope or cable q thereof, and at the same time turning, by means of the hand-wheel n, the threaded 85 or nut-like sprocket-wheels m (which are banded together by the chain belt M) in such manner and to such extent as to cause them to take up or draw backwardly in a proper manner the screw-rods J, and to thus shift 90 the position of the cross-head E and the wheel B, suspended therefrom, in such manner as to prevent any undue slack in the conveyer-chain. Before reversing the direction of run of the chain conveyer from the condition illustrated by the full lines at Fig. 2 the suspended wheel B, together with its axle g and V-shaped suspended devices h, is turned over or made to perform about a half-revolution 95 about the axis of the swivel i as an axis of motion, which brings the flights f of the chain D into the reverse position from that shown in full lines at the upper part of Fig. 2 and into the position indicated where said chain and flights are drawn in dotted lines, and of 100 course at the same time the lower portion of the endless conveyer-chain is similarly reversed in position either by turning over, by hand or otherwise, the shaft on which the drive-wheel c is mounted, or (in case said 105 wheel be keyed on the end of the drive-shaft) by simply unshipping the chain from said wheel after having suitably slackened up the chain and reversing its position on the wheel.

In the contrivance shown and described in 110 my other application it is necessary, in order to use the apparatus for the two purposes of accumulating and removing piles of material, to have the entire run of the chain conveyer made with two sets of flights—one adapted 115 to operate in one direction for the purpose of piling up the material and the other to operate in the opposite direction for the purpose of removing the pile of material.

In my present improved contrivance, it will be seen, I dispense with the extra set of flights, make the chain conveyer after the usual simple pattern or fashion, and render it capable of use for the two purposes mentioned by turning the whole conveyer device about a half-revolution on an imaginary axis about coincident with the line passing from end to end through the double run of conveyer-chain. By this improvement I am enabled to not only simplify the construction of the chain conveyer, but to very materially reduce its aggregate weight, which in the case of a suspended conveyer—such as used in both the present and my other contrivance—is a great desideratum.

The details of construction by which I am enabled by means of the swivel-like action to turn or shift the upper end of the suspended chain conveyer without deranging or interfering with the suspending mast or pole and the devices depending therefrom will be best understood by reference to the enlarged views of these devices seen at Figs. 3 and 4.

I have not shown or illustrated any mechanical appliances by which the turning over end for end of the shaft of the drive-wheel *c*, or the shifting of the chain on the drive-wheel, may be conveniently accomplished, as I do not deem this necessary; and I wish it to be understood that, while I have shown the swivel device illustrated as a con-

venient means for making a half-turn in or shifting the position of the upper end of the chain conveyer, my invention does not rest 35 in and is not restricted to any particular means or devices for effecting the turning or adjustment of the endless chain of the conveyer at either of its ends, the pith of my invention resting in a reversible chain conveyer 40 having a single series or set of flights, thus adapted to operate in either of two directions for either one of the two purposes hereinbefore described.

What I therefore claim as new in this application, and desire to secure by Letters Patent, is—

In an apparatus or contrivance for conveying coal and other material from a given source of supply and forming the same into 50 an extensive heap or pile, and for also reconveying such matter from the pile or heap back to a given point or locality for transportation, the reversible chain conveyer, in combination with means whereby said conveyer 55 may be bodily reversed, substantially in the manner and for the purpose hereinbefore set forth.

In witness whereof I have hereunto set my hand this 10th day of October, 1887.

JAMES M. DODGE.

In presence of—

EDW. W. RHODES,
M. GETZ.
